(57) **CLAIM**

The ornamental design for a shaping jumpsuit as shown and described.

DESCRIPTION

FIG. 1 is a front perspective view of a shaping jumpsuit showing our new design;

FIG. 2 is a front view thereof;

FIG. 3 is a rear view thereof;

FIG. 4 is a left side view thereof;

FIG. 5 is a right side view thereof; and,

FIG. 6 is a rear perspective view thereof.

The broken lines forming the mannequin are for environmental purposes only and form no part of the claimed design. All broken lines within the bounds of the garment depict stitching that forms part of the claimed design.
